HAIR RETAINER COMB

Abraham Goodman, New York, N.Y., assignor to H. Goodman & Sons, Inc., New York, N.Y., a corporation of Delaware

Filed Dec. 6, 1960, Ser. No. 63,134

Term of patent 14 years

(Cl. D86—10)

Fig. 1.

Fig. 2.

Fig. 3.

Fig. 4.

FIGURE 1 is a front elevational view of a hair retainer comb showing my new design.

FIGURE 2 is a sectional view taken on line 2-2 of FIGURE 1.

FIGURE 3 is a sectional view taken on line 3-3 of FIGURE 1.

FIGURE 4 is a top plan view.

My design comprises a series of bifurcated tooth sections forming points at the lower end and pearized head members joining the legs of each adjacent tooth all as shown.

I claim:

The ornamental design for a hair retainer comb, substantially as shown and described.
